METHOD OF PRODUCING WATER GAS.

Application filed July 15, 1922. Serial No. 575,254.

- This invention relates to a new and improved method of producing water gas. Our method has for its object the carbonizing of a relatively deep bed of coal by passing gases through the fuel bed, which consists of several superimposed layers of coal on top of hot coke, the purpose being to preheat the upper layers with the gases passing through from the lower layers and of compressing the lower layers by the weight of the upper layers in order to increase the speed and efficiency of the carbonizing process and producing more solid coke for use in making water gas. We have found that by externally preheating the gases passing through a raw fuel bed, blue water gas making can be carried on with layers of bituminous coal several feet in thickness placed upon the coke, whereas present day practice in which carbonization without preheating is used limits the coal bed to less than one foot in thickness. We have by experiments found that the method herein described actually preheats the upper layers of coal and at the same time compresses the lower layers of coal, thereby making a more solid coke, more suitable for subsequent gas making. The process is carried out by charging an ordinary water gas generator with coke and by alternately air blasting and steaming, bringing the fuel charge up to the gas making temperature. The heat carried out of the generators by the blast gas is stored in suitable air or steam regenerators, or both. When the coke has reached a proper depth and these regenerators have reached a proper temperature, the actual process of carbonization begins. At this point the first layer of coal is dropped on top of the hot coke in the generator. The preheated steam from the regenerators is then introduced into the bottom of the generator and sent upward through the hot coke, producing highly heated blue water gas which continues upward through the layer of raw coal just charged. This operation results in the rapid heating of the coal and the immediate volatilization of some of its volatile matter and is continued long enough sufficiently to fuse the coal to render it suitable for the successive air blasting period, that is, to prevent the carrying out of small particles of solid fuel with the blast gases. Means are provided for agitating the fuel and this agitation is particularly important when using fuels which tend to mass and fuse together. The poking or agitation keeps the mass broken up and insures the passage of the hot gases uniformly throughout the fuel. It minimizes channeling and the formation of uncoked masses and aids materially in preventing clinkering. At the end of this period the making of water gas is resumed and continued until the coke has regained its proper temperature, when a second layer of coal is added. The operation is continued exactly as before. The highly heated gases passing upward continue the carbonization of the first layer of coal and start the carbonization of the next layer of coal. The operation may be continued in this manner until a sufficient thickness of the coal bed has been reached to give the best results, in regard to utilization and distribution of the hot gases through the coal bed, as well as in regard to the compressing of the lower layers of coal by the superimposed weight for the purpose of producing a more solid coke. After a sufficient thickness of coal is added, the amount of water gas made is such as to keep the level of the coke at the proper height for efficient operation. In other words, new layers of coal are added at regular intervals to keep the generators full so that a continuous operation results and the maximum efficiency is derived. This process may be carried out either in a single generator where the carbonizing of the fuel is accomplished both by hot blue water gas and air blast gases passing through the fuel or can be applied in the case of a cyclic operation in which by the use of several sets blue water gas only is passed through the fuel as a carbonizing medium. We have illustrated an apparatus adapted for carrying out our process in the accompanying drawings, in which—

Figure 1 is a somewhat diagrammatic plan view partly in section, showing a water gas generator and the accompanying stoves, and

Figure 2 is a vertical section taken approximately on line 2—2 of Figure 1.

The water gas generator unit A is of the

usual type, comprising the shell 5 and refractory lining 6. It is provided with the fuel charging opening 7 and the grate 8. The usual doors 9 are provided for removal of clinkers, as is also the usual ash cleanout door 10. The passage 11 is provided for the withdrawal of the gas as made, this passage being controlled by valve 12.

The top of the water gas generator A is connected by passage 13 with the top of the steam heater B, the passage being controlled by valve 14. The passage 15 leads from the passage 13 adjacent the heater B and is connected at 16 to the unit A at a point below the grate. The passage 15 is controlled by valve 17.

The heater B is connected with air stoves C and D by passages 18 and 19, respectively, these passages being controlled by valves 20 and 21. The stoves C and D are provided with exhaust passages 22 and 23, respectively. These stoves are also provided with intake passages 24 and 25, respectively, for the introduction of air, these passages being controlled by valves 26 and 27. The stove C is connected by passage 28 to the unit A at a point below the grate, this passage 28 being controlled by valve 29. The stove D is similarly connected to the unit A by passage 30 controlled by valve 31. The steam heater B is provided with the intake passage 32 controlled by valve 33. The poker or stirring rod 34 is shown as inserted through the top covering the opening 7 and the poker may be rotated and reciprocated by any suitable means (not shown). Such devices are old in the art in connection with gas producers.

In the operation of the installation, the unit A is partially filled with coke or similar carbonaceous residue. Air is introduced through passage 24 to stove C and passes thence through passage 28, past valve 29, to the lower portion of the gas making unit. This air flows up through the grates and passes through the mass of carbonaceous residue, causing combustion, which raises the temperature of the residue. The air blast gases are led out through passage 13, valve 14 being open, to the steam heater B. It will be understood that valve 17 is closed, as is valve 33. The hot blast gases pass down through the heater B and through passage 19, past valve 21, to the air stove D. Air may be introduced to burn the blast gases if desired. The valves 31 and 27 are closed and the blast gases pass out of the stove through discharge passage 23. They may be exhausted to the atmosphere or their remaining heat may be utilized in other stoves or in waste heat boilers, as desired.

When the stove D has been sufficiently heated, the operation will preferably be partially reversed to the extent that the incoming air will be introduced through stove D and through passage 30 to the unit A, while the

blast gases will be passed out through stove C from the steam heater B. The stove D serves to preheat the air.

When the carbonaceous residue is at a temperature adequate for the production of water gas, the air blast is stopped, valves 29 and 31 both being shut off. Valve 14 is closed and valve 17 is opened. A layer of coal or other raw fuel is now placed upon the heated residue.

Steam is then introduced through passage 32, past valve 33, and passes upwardly through the highly heated steam heater B in which it is preheated. The preheated steam is led through passages 13 and 15 and is introduced into the gas making unit below the grate. This highly heated steam passes up through the heated mass of carbonaceous residue and water gas is evolved. The heated water gas passes up through the raw fuel on the residue and carries off volatile contents from the fuel. The gases and vapors are led off through passage 11, past valve 12, to any suitable washing and scrubbing apparatus, and then to a gas holder or other apparatus, as may be desired. It may be passed through a superheater to fix the volatile content or through a carburetor for adding enriching material before being passed to a superheater.

Due to the high temperature to which the residue has been raised, and the high temperature of the steam, the water gas reaction takes place rapidly and efficiently. The residue is not materially chilled by the introduction of the steam since the steam is at a temperature approximately that of the residue.

The process is continuous and when the heater B has had its temperature reduced in heating the incoming steam, and when the temperature of the carbonaceous residue has become lower than that suitable for efficient operation, the process is again reversed and the residue is blasted by air heated in either of the stoves C or D, whichever may have last been heated by the passage of blast gases.

Another layer of coal or raw fuel is now placed upon the mass of material in the unit and the process continues as before. The fuel is preferably introduced in relatively thin layers at comparatively short intervals and may be stirred by the poker during the gas making process.

The unit will become filled to the proper working height by the successive layers of fuel, the lowermost layer being gas making coke or the equivalent and the top layer relatively raw fuel. The fuel is gradually coked or reduced to carbonaceous residue suitable for gas making as it works its way down the unit. It will be understood that the ash is periodically removed from below the grate.

The weight of the superposed column of

material is an important factor in assuring that the coke or carbonaceous residue in the gas making zone is of a suitable texture and quality for gas generation.

5 While it has been stated that the layers of raw fuel are added after a period of air blasting and before the subsequent gas making period and this method is considered preferable, it is not essential. When the unit is 10 fully in operation, the amount of fuel added will correspond to that reduced to ash in gas generation during the corresponding period.

15 The operation may be varied in many ways within the scope of the appended claim; for instance, it may prove more economical to add more heat to the air and less or more to the steam.

We claim:

The method of water gas production which

comprises, air blasting a mass of carbonaceous residue to raise its temperature, placing a layer of coal on said residue, passing steam into said heated residue to form blue water gas, passing the heated blue water gas through the coal, whereby the heat of the blue water gas serves to volatilize the volatile content of the coal, agitating the layer of coal during the passage of the blue water gas, and continuing the process by alternately air blasting and then adding coal and passing steam into the mass of residue, the blue water gas passing through the added coal, the blast air and the steam being both preheated by heat derived from the air blast gases.

Signed at Chicago, Illinois, this 12th day of July, 1922.

CHARLES W. ANDREWS.
